STOWAGE RACK

John L. Torresen, Grimes Hill, N.Y., assignor to Bell Telephone Laboratories, Incorporated, New York, N.Y., a corporation of New York

Filed Nov. 16, 1962, Ser. No. 72,521

Term of patent 14 years

(Cl. D41—1)

FIG. 1

FIG. 2

FIG. 3

FIG. 1 is a perspective view of my new design for a stowage rack;

FIG. 2 is a side elevational view of the stowage rack showing the new design; and

FIG. 3 is an end elevational view of the stowage rack. I claim:

The ornamental design for a stowage rack, as shown.
